UNITED STATES PATENT OFFICE.

WILLIAM H. MUSSEY, OF LONG ISLAND, NEW YORK.

DRAFT-RIGGING.

No. 926,351.

Specification of Letters Patent.

Patented June 29, 1909.

Application filed December 17, 1908. Serial No. 468,028.

To all whom it may concern:

Be it known that I, WILLIAM H. MUSSEY, a citizen of the United States, residing at Long Island, in the county of Queens and 5 State of New York, have invented certain new and useful Improvements in Draft-Rigging, of which the following is a specification.

This invention relates to improvements in 10 draft mechanisms for railway cars.

One of the objects of the invention is to provide a device of the character described which comprises a minimum number of parts that may be readily assembled and 15 disassembled.

Another object contemplated by this invention is the provision of a draft-rigging which requires only drilling, thus dispensing with the machine work which is necessary in constructing the several component 20 parts of similar devices.

Still another object sought by this invention is to so construct the device that all parts thereof will be exposed for purposes 25 of inspection.

Other objects of the invention are to obtain the maximum efficiency of strength proportionate to the weight; to provide for low cost of maintenance, cheapness and rapidity 30 of construction; and to afford the greatest possible amplitude of lateral oscillation in the draw-head and draft-iron.

To the accomplishment of the recited objects and other coördinate therewith, the 35 preferred embodiment of the invention resides in that arrangement and construction of parts hereinafter described, illustrated in the accompanying drawings, and embraced within the scope of the appended claims.

In said drawings: Figure I is a side elevation of the device embodying my invention, one of the proximal ends of the draft-bar being broken away to show the construction 40 of the barrel. Fig. II is a top plan view of the device. Fig. III is a bottom plan view of the draw-bar and a portion of the outer terminal of the draft-bar, and Fig. IV is a side elevation thereof, the cross beam 45 and support being shown in section. Fig. V is a transverse sectional view taken along lines 5—5 of Fig. I. Fig. VI is an elevation in detail of the draft-iron. Fig. VII is a fragmentary side elevation of the barrel and one of the collars. Fig. VIII is a side 55 elevation of one of the key-plates, and Fig. IX is an end elevation thereof. Fig. X is a

transverse sectional view taken along lines 10—10 of the draft-bar, and Fig. XI is a similar view taken along lines 11—11 of Fig. I.

Like reference characters indicate corresponding parts throughout the several views.

Generally speaking, the invention embraces a draft-bar adapted to be secured to the bolster or under timbers of a car frame 65 in such a manner as to preclude possibility of contact with, or injury to, the motor or other running gear, one of the opposed terminals of said draft-bar being arranged to receive any well known type of coupler, and the other affording means for thoroughly absorbing the shock incident to the draft and buffing movements of adjacent cars.

Referring more particularly to the drawings for a detail description of the invention, the numeral 5 designates a cast steel draft-bar which is obtuse angled, the lower horizontal extremity having the conformation of an ordinary 80 lb. rail, as clearly shown in Fig. XI of the accompanying drawings, and presenting a slightly different cross sectional contour from its point of deflection to a point adjacent the inner distal end of the barrel, as exhibited in Fig. X. Again it will be noted that the horizontal extremity of this draft-bar is provided on opposite sides of the wedge (6) with a plurality of integrally formed projections or "chipping strips" (7), the latter being apertured, as at 8, to facilitate the insertion of rivets when mounting the draw-bar (9), which in the present instance is of the well known Van Dorn type. In the assemblage of the draw-bar and the draft-bar in the manner just explained these "chipping strips" afford ample and reliable bearing at points where riveting is done, thus eliminating the machining of this casting. As hereinbefore intimated, the opposite extremity of the draft-bar (5) which is circular in cross section is cored longitudinally for a suitable distance to form a casing or barrel (10) with a diameter sufficiently large to permit of a free sliding of the draft-iron (11) relative therein, the latter being of axle steel and pivoted in the usual way to the 90 under frames of a car.

At diametrically opposite sides of the barrel (10), and preferably at the proximal end thereof is a pair of elongated slots (12), a similar pair of slots (13) being arranged 95 on the corresponding portions of the draft-iron (11). By virtue of the disposition of

these slots an exact registration thereof may be readily effected for the purpose to be presently set forth.

Mounted exteriorly of the barrel (10) and having a curvature complementary to the curvature of said barrel is a pair of cast steel collars (14), each of said collars being equipped with integral pairs of outwardly directed lateral ears (15) to form a receptive space for the outer terminal portions of the key-bars (16), which are clearly illustrated in Figs. VIII and XI of the drawings. The key-plates are identical in construction and comprise a substantially quadrilateral piece of axle steel which is rabbeted or cut away, as at 17, to present a pair of projections (18) which are designed to engage the corresponding opposite sides of the barrel (11) and prevent dislodgment or derangement of the key-plates, one of the keys being preferably beveled at 19 to assist in directing the same through the slots (12 and 13) in the course of assembling the rigging. Manifestly, the outer ends of each key, as well as the ears (15) of the collars (14) are apertured at 20 and 21, respectively, to permit the insertion of a cotter pin (22).

A strong coil spring is positioned intermediate the inner faces of the collars (14) and encircles the barrel to absorb the shock resulting from either the draft or buffing to which the device is subjected, as will be readily comprehended by those skilled in the art.

It should be understood that in its broader aspect the invention comprehends the employment not only of the various means described, but of equivalent means for performing the recited functions. To exemplify, applicant does not wish to be limited to the use of the Van Dorn type of coupler, the spring device, and the application of the invention as an entirety to railway cars as it will appear manifest that any type of coupler, draft rigging and vehicles of any description may be utilized in conjunction with the invention.

While the arrangement shown is thought at the present time, to be preferable it is desired to reserve the right to effect such modifications and variations thereof as may come fairly within the scope of the appended claims.

Having thus described the invention what is claimed as new is:

1. In a device of the character described, the combination of a draft-bar having a barrel, a draft-iron adapted to be inserted in said barrel, a pair of collars slidably

mounted on said barrel, shock absorbing means arranged intermediate said collars, means extending through said barrel and draft-iron and connected to opposite faces of each collar, and means for mounting a draw-bar on said draft-bar.

2. In a device of the character described, the combination of a draft-bar having a barrel, a draft-iron adapted to be inserted in said barrel, a pair of collars slidably mounted on said barrel, means arranged intermediate said collars for absorbing the shock resulting from either the draft or buffing of adjacent cars, and means for mounting a draw-bar on said draft-bar.

3. In a device of the character described, the combination of a draft-bar having a barrel, a draft-iron adapted to be inserted in said barrel, said draft-bar and draft-iron having pairs of slots, a pair of collars slidably mounted on said barrel, shock absorbing means arranged intermediate said collars, means extending through said slots and connected to opposite sides of each collar, and means for mounting a draw-bar on said draft-bar.

4. In a device of the character described, the combination of a draft-bar having a barrel, a draft-iron adapted to be inserted in said barrel, said draft-bar and draft-iron having pairs of slots, a pair of collars slidably mounted on said barrel and provided with lateral projections, tension means arranged intermediate said collars, key-plates extending through said slots and connected to said projections, and means for mounting a draw-bar on said draft-bar.

5. In a device of the character described, the combination of a draft-bar and a draft-iron, and means surrounding and connected to said draft-bar and draft-iron for absorbing the shock resulting from either the draft or buffing of adjacent cars.

6. In a device of the character described, the combination of a draft-bar, a draft-iron, a draw-bar, means associated with said draft-bar and draft-iron for absorbing the shock resulting from either the draft or buffing of adjacent cars, and a plurality of spaced projections on opposite sides of said draft-bar having openings for the reception of fastening means for said draw-bar.

In testimony whereof I affix my signature, in presence of two witnesses.

WILLIAM H. MUSSEY.
